UNITED STATES PATENT OFFICE.

CHARLES AUGUSTUS HAGERTY, OF LOS ANGELES, CALIFORNIA.

GAME APPARATUS.

1,138,865.

Specification of Letters Patent.

Patented May 11, 1915.

Application filed August 3, 1914. Serial No. 854,881.

To all whom it may concern:

Be it known that I, CHARLES AUGUSTUS HAGERTY, a citizen of the United States, residing at Los Angeles, in the county of Los Angeles and State of California, have invented a new and useful Game Apparatus, of which the following is a specification.

My invention relates to game apparatus, and more particularly to that class of game apparatus in which a missile or projectile is discharged at a target, and one of the main objects of my invention is to produce a game apparatus of the class described of simple form and construction in which the reward of the game depends upon the skill of the player in projecting a missile into apertures in a moving target.

Another object of my invention is to produce a game apparatus of the class described in which a moving target provided with receiving apertures is arranged in such a manner as to deliver the missile entering such apertures into predetermined pockets respectively of different values arranged in a stationary portion of the apparatus.

Other objects and advantages will appear hereinafter.

Referring to the drawings, which are for illustrative purposes only: Figure 1 is a side elevation of a game apparatus embodying a form of my invention. Fig. 2 is a longitudinal sectional view of the apparatus shown in Fig. 1. Fig. 3 is a plan view, partly in section, of the apparatus shown in Fig. 1. Fig. 4 is a plan view of a portion of the apparatus shown in Fig. 1, the revolving table and gun being removed.

The apparatus consists of a base 1 supported on suitable legs 2, the base 1 being designed to be placed upon any suitable object to support the same at approximately the height of an ordinary table. Secured to the underside of the table is a sheet metal member 3 bent to form a series of runways 4, 5, 6, 7, 8, 9, 10, 11 and 12, the runways being inclined downwardly toward the front of the apparatus and terminating in pockets 13, 14, 15, 16, 17, 18, 19, 20 and 21 respectively. Secured to the upper side of the base 1 is a distributing box 24 being provided with an outer concentric channel 25 and a series of inner concentric channels 26, 27, 28, 29 and 30, the channels 26 to 30 inclusive each being provided with a single high portion 31 and a low portion 32 so arranged that a ball will roll from the high

portion to the low portion and drop downwardly therefrom through outlet openings 26', 27', 28', 29' and 30' respectively, the openings 26' to 30' registering with passages α through the base 1 forming continuations of the respective outlet openings in the channels into the respective runways below the base.

The channel 25 is provided with a plurality of outlet openings indicated at 35, 36, 37 and 38, the said channel 25 having a high portion and a low portion for each of the openings 35 to 38 inclusive, so that a ball dropping into the channel 25 will roll into the respective outlets, depending upon which portion of the channel 25 the ball should fall into. Mounted in the base 1, centrally of the distributing box 24, is a bearing 40 which extends upwardly therefrom to the same height as the top of the distributing box 24. 41 designates a spindle rotatably mounted in the bearing 40 and provided with a flange 42 to which is secured a rotatable table or target 43 provided with a series of apertures extending inwardly from the outer face thereof and designated at 45, 46, 47, 48 and 49 respectively. The apparatus 45 to 49 respectively are arranged radially with respect to the spindle 41 and are formed so that the floor or bottom of the respective apertures is depressed downwardly toward outlet passages 45', 46', 47', 48' and 49' in the bottom of the respective apertures. Each aperture 45' to 49' respectively is provided at the mouth or entrance end thereof with a gate indicated at 51 formed of wire, the ends 52 of which extend into the walls of the aperture in such a manner that the respective gates may swing freely inwardly and assume a vertical or closed position when not operated. The lower end 53 of the respective gates engages a shoulder 54 formed at the mouth of each respective aperture, whereby the gates are prevented from swinging outwardly by contact from the interior of the aperture. The table 43 terminates in a circular trough indicated at 55 which is provided with a series of discharge or outlet openings 56, 57, 58 and 59, the trough 55 being provided with a series of high portions 60 located between the respective discharge outlets, so that a ball or missile will roll away from the respective high portions 60 to the outlet openings. Mounted by means of a suitable bracket 61 secured to the base 1 is a motor 62 which may be of

any suitable form of construction, in the present instance being a spring motor provided with a winding key 63 and governor means 64, the motor being connected by means of suitable gearing indicated at 65 with the spindle 41 of the table 43.

Mounted at the front end of the base 1 is a gun 66 provided with a barrel 67 having an opening 68 in the top thereof for the insertion of a ball or missile indicated at 70.

71 designates a spring actuated follower controlled by trigger mechanism 72 mounted on the handle 73 of the gun.

The operation of the game apparatus is as follows: Assuming that the ball 70 has been loaded into the gun and that the trigger has been pulled, Fig. 2 would illustrate the relative position of the parts at the time the ball is moving in the direction of the arrow out 15 of the gun toward the target, namely, the rotating table, the table having been first set in rotatable motion by means of the motor 62. The ball leaving the gun would be discharged against the face of the table 43 and 20 in the event that one of the apertures should be in line with the gun at the proper instant, the ball would enter such aperture. In the present instance, assuming that the ball entered the aperture 46, the gate 51 therein 25 would swing inwardly admitting the ball to the aperture, and the same would roll toward the discharge outlet 46' therein. It is to be noted that the discharge outlet 46' of the aperture 46 is at all times over the concentric channel 30 in the distributing box 24 and a ball passing through the outlet 46' would drop into the channel 30. The ball in 30 the channel 30 would roll toward the discharge opening 30' therein and drop downwardly through such opening, and the continuation α thereof in the base 1, into the runway 8 immediately below the opening 30', the ball moving down the runway 8 into 35 pocket 17. Should the ball enter aperture 40 47 it will pass downwardly through outlet 47' into channel 29 in the distributing box, thence through discharge opening 29' in the channel, and opening α thereunder, into runway 7 and be discharged into pocket 16. 45 The course of a ball entering apertures 48, 49 and 45 would be through respective openings 48', 49' and 45' into the respective channels 28, 27 and 26 in the distributing box and be discharged respectively through 50 openings 28', 27' and 26' into respective runways 9, 6 and 10, thence into respective pockets 18, 15 and 19. In the event that a ball when discharged from the gun should strike the face of the table 43, the ball, 55 should it rebound toward the gun, would strike against walls 75 of a deflector 76 and roll into the circular trough 55 of the table. The position of the table would determine 60 whether such ball would pass through discharge openings 56, 57, 58 or 59 in the 65

trough, and the position of the table with relation to the distributing box would determine through which opening 35, 36, 37 or 38 in the concentric channel 25 the ball would pass, the ball passing through opening 35 70 being delivered into runway 12, thence into pocket 21. A ball delivered through opening 36 would pass into runway 11, thence into pocket 20. A ball passing through opening 37 would be delivered into runway 75 5, thence into pocket 14. A ball discharged through opening 38 would be delivered into runway 4, thence into pocket 13. It is to be noted that the width of the mouth or entrance of the respective apertures 45 to 49 80 inclusive in the table is varied, and that the pockets in the base may be numbered to designate the reward the player will have upon operating the game. The ball entering the aperture of narrowest width eventually passes into the pocket having the highest reward. In the present instance, I have shown the pockets numbered so that the player who is skilled enough to fire a ball into the narrowest aperture 46 in the 90 table will count 7, as indicated in pocket 17. The ball discharged into aperture 47, passing eventually into pocket 16, receives 5 as a reward. The ball entering aperture 48, eventually discharging into pocket 18, receives 4 as a reward. The ball entering aperture 49, eventually passing into pocket 15, receives 3 as a reward. The ball entering aperture 45, eventually passing into pocket 19, receives 2 as a reward. 100

It is understood that the ball entering the trough 55 on the table may eventually pass, as heretofore described, into either pocket 13, 14, 20, or 21, and I have marked the same "One more shot," "1," "Go back 5," and 105 "Go back 3" respectively. It is further understood that the pockets may be marked with any suitable markings, the markings disclosed in Figs. 3 and 4 simply being for 110 illustrative purposes.

Attention is directed to the fact that the skill of the player comes into play in being able to discharge a ball from the gun into the apertures in the table of smallest width, as the smaller the aperture the greater the 115 reward.

What I claim is:—

1. A game apparatus comprising a stationary base having a series of pockets therein, a rotatable table mounted on said base, 120 said table having a series of radially arranged apertures extending inwardly from the outer face thereof, means for discharging a missile into said apertures, and means whereby a missile received in an aperture in 125 said table is delivered into a predetermined pocket in said base.

2. A game apparatus comprising a stationary base having a series of pockets therein, a distributing box on said base having a 130

series of channels therein each having outlet means to a predetermined pocket, a rotatable table mounted on said base, said table having a series of apertures therein, each of 5 said apertures having outlet means into a predetermined channel in said distributing box, and means for discharging a missile into the apertures in said table.

3. A game apparatus comprising a stationary base having a series of runways each 10 terminating in a pocket, a distributing box on said base having a series of concentric channels therein each having an outlet to a predetermined runway, a rotatable table 15 mounted on said base, said table having a series of apertures therein, each of said apertures having outlet means into a predetermined channel in said distributing box, means for rotating said table, and means for 20 discharging a missile into the apertures in said table.

4. A game apparatus comprising a base having a series of pockets supported thereby, a rotatable table mounted on said base, 25 said table having a series of apertures therein, gate means at the mouth of each aperture, means for discharging a missile into said apertures, and means for delivering a missile from any of said apertures into a 30 predetermined pocket.

5. A game apparatus comprising a base having a series of pockets supported thereby, a rotatable table mounted on said base, said table having a series of apertures extending inwardly from the face thereof, a 35 gate in the mouth of each aperture, means for pivotally mounting said gates to permit

the same to swing freely inwardly, means for preventing the gate from swinging outwardly, means for discharging a missile into 40 the apertures in said table, and means for conducting a missile from any of said apertures to a predetermined pocket.

6. A game apparatus comprising a stationary base having a series of runways each 45 terminating in a pocket, a distributing box on said base having a series of concentric inner channels and a concentric outer channel, said inner channels each having an outlet in the bottom thereof in open communication 50 with one of said runways, said outer channel having a series of outlets in the bottom thereof each in open communication with one of said runways, a rotatable table on said base, said table having a series of apertures 55 therein, each of said apertures having an outlet opening in the bottom thereof in open communication with one of said inner concentric channels, a circular trough around the outer edge of said table, said 60 trough having a series of outlet openings in the bottom thereof in open communication with the outer concentric channel in said box, means for discharging a missile into 65 said apertures, and means for rotating said table.

In testimony whereof, I have hereunto set my hand at Los Angeles, California, this 24th day of July, 1914.

CHARLES AUGUSTUS HAGERTY.
